FIRE EXTINGUISHER

Filed Nov 26, 1927

Inventor:
Louis Brillou
per Fred F. Burton
Attorney.

UNITED STATES PATENT OFFICE

LOUIS BRILLOU, OF PARIS, FRANCE

FIRE EXTINGUISHER

Application filed November 26, 1927, Serial No. 235,948, and in France December 4, 1926.

My invention relates to fire extinguishers and more particularly to the type having total obturation.

The accompanying drawing, shows by way of example, one form of execution of the invention, representing a partial longitudinal section through an extinguisher.

Referring to the drawing, on a hollow sheet metal cylindrical receptacle 1 is welded 10 a threaded collar 2, which receives a closing device 3, fluid tightness being assured by means of a rubber washer 4. A threaded sleeve 5 provided with an inturned circular flange 5' extending at right angles to the 15 sleeve 5 allows assembling and tightening of the closing device 3.

The said closing device comprises a cylindrical metallic piece provided with a recess 6 and a lower reduced portion 7, tapped to 20 receive a threaded extremity 8 of a fitting 9. The said fitting 9 is provided at its extremity with an operating handle 10 and a stuffing box 11 adjacent thereto. At a point near the middle is provided a closing 25 valve 12. On the interior of the fitting 3 is provided an annular shoulder 14 cooperating with the valve 12. The wall of the fitting 3 is provided with a series of openings 15, slightly inclined and at a point below the valve seat 14. The recess 6 of fitting 3 above the valve 12 is placed into communication with the atmosphere by means of an evacuation conduit 16 which may be furnished with a valve if desired.

35 The second receptacle 17 containing one of the chemical solutions is adapted to slide into the first cylindrical receptacle 1. A flange 18 maintains the two receptacles concentric with respect to each other. Slightly 40 below its upper extremity, the receptacle 17 is provided with a cover 19 welded thereto and possessing a filling orifice 20. Closing of the orifice 20 is produced by means of a conical plug 21 of rubber or other appropriate material carried by the extremity of a rod 22 slidably mounted in the extremity of fitting 9. The said rod is provided with an enlarged head 22' against which abuts a spring 23 and is prevented from leaving 45 the fitting by means of a threaded collar 24

provided in the end of fitting 9. A circular guide washer 26 guides the rod 22 in the upper portion 27 of the receptacle 17 which is above the cover 19. The portion 27 is furnished with perforations 28 on its periphery which open into the receptacle 1. Two handles 29 are provided on the exterior of the receptacle 1 for permitting the apparatus to be manipulated in the usual manner.

The operation of my device is as follows:

When the apparatus is charged, that is, after the receptacles 1 and 17 have been filled with aciduous, bicarbonated, or other suitable solutions, the receptacle 17 is slid into the receptacle 1 through the opening in the ring 2. The closing device 3 is then placed upon the ring 2 and secured in place by the ring 5, compressing the rubber ring 4 sufficiently to produce fluid tightness. In turning the fitting 9 by means of the handle 10 thereof, the valve 12 is seated and closes the apparatus hermetically, that is to say, prevents the solution contained in receptacle 1 to be diverted through the conduit 16. At the same time, the plug 21 becomes seated in the orifice 20 through the action of the spring 23 on its rod 22. By tightening the fitting 9 the tension of the spring 23 can be increased at will and obtain a perfect obturation of the receptacle 17. Under these conditions it is impossible that the two solutions become mixed even if the apparatus is turned over.

In order to cause the extinguisher to function it is merely necessary to loosen or unscrew the fitting 9 by means of the handle 10 and turn the apparatus over. As soon as the mixture of the two solutions takes place disengagement of the carbonic acid is obtained carrying with it the foam formed by Panama wood in the usual manner

Having thus described my invention what I claim as new and desire to secure by Letters Patent is:

1. In a fire extinguisher the combination of an exterior chemical receptacle, a concentric inner receptacle fixed in said first receptacle, a common outlet for said receptacles, a manually controlled valve for said outlet, a spring-pressed valve carried by said first mentioned valve for closing said inner

receptacle, and means for guiding said spring-pressed valve.

2. In a fire extinguisher the combination of an exterior chemical receptacle, a concentric inner receptacle fixed in said first receptacle, a common outlet for said receptacles, a manually controlled valve for said outlet, a spring-pressed valve carried by said first mentioned valve for closing said inner receptacle, and a disk fixed to said second valve adapted to slide on the interior of said inner receptacle for guiding said spring pressed valve.

3. In a fire extinguisher the combination of an exterior chemical receptacle, a concentric inner receptacle, a common fitting for closing said receptacles, a common outlet formed in said fitting for said receptacles, a manually controlled valve for said outlet, a perforate partition disposed in said inner receptacle, a conical spring-pressed valve carried by said first mentioned valve adapted to close said partition, and a disk fixed to said second valve adapted to slide on the interior of said inner receptacle for guiding said spring pressed valve.

In testimony whereof, I have signed my name to this specification at Paris, France, this 18th day of November, 1927.
